UNITED STATES PATENT OFFICE.

CHARLES W. GLIDDEN, OF LYNN, ASSIGNOR TO JAMES W. BROOKS, TRUSTEE,
OF PETERSHAM, MASSACHUSETTS.

HEEL COMPRESSING AND LOADING MACHINE.

SPECIFICATION forming part of Letters Patent No. 502,668, dated August 1, 1893.

Application filed January 3, 1893. Serial No. 457,094. (No model.)

To all whom it may concern:

Be it known that I, CHARLES W. GLIDDEN, of Lynn, county of Essex, State of Massachusetts, have invented an Improvement in Heel 55
5 Compressing and Loading Machines, of which the following description, in connection with the accompanying drawings, is a specification, like letters and numerals on the drawings representing like parts.

10 This invention has for its object to simplify and improve the apparatus shown in my application, Serial No. 432,167, filed May 7, 1892. In that application I have shown two rotary tables or carriers, one for moving a series of 60
15 nail boxes, and the other a series of heel seat dies, and also a set of awls and a set of drivers, the heel being pricked in a compressing die and being thereafter carried by the heel seat dies in line with the loaded nail-box and 65
20 the drivers. In this present invention I have dispensed with the series of heel seat dies and their rotating carrier, and with the awls for pricking the heel, and instead I deposit the heel to be filled with nails from the automatically 70
25 loaded nail box, upon a heel seat die mounted upon a rising and falling die plunger, the latter effecting the placing the heel blank in a heel compressing die adapted to compress the heel from edge to edge, and 75
30 at the same time the heel seat die in its vertical movement co-operates with a yielding or other abutment and compresses the heel vertically. This vertical compression of the heel, however, is effected against the bottom 80
35 of the table or carrier upon which rests the loaded nail boxes, and the drivers, connected with a suitable driver bar, drive the nails directly from a nail box into a heel, this being practical in many classes of heels now used. 85
40 In this present invention I have provided the driver-bar with a suitable rack or projection to actuate, at the proper times, mechanism for automatically assorting and distributing nails into the nail boxes, the nail assorting 90
45 and distributing mechanism being substantially the same as in said application. During the operation of driving the nails from the nail box into a compressed heel, the drivers descend through a guide plate, which is 95
50 held pressed firmly down against the nail box during the heel compressing and nail driving

operations, but when the carrier for the nail boxes has to be moved this driver guide plate, performing the function of an abutment, is slightly lifted to thus free the nail box from the friction of the plate, in order that the nail box and carrier may be moved freely with the minimum of power.

The peculiar features in which this invention consists will be hereinafter more fully described and pointed out in the claims at the end of this specification.

Figure 1 of the drawings in side elevation, shows a sufficient portion of a heel compressing and loading machine to enable my invention to be understood; Fig. 2, a partial front or left hand elevation of the machine shown in Fig. 1; but with the nail assorting and distributing mechanism removed; parts of the devices being in section to better illustrate the construction and operation of the machine; Fig. 2^a, a detail of the lower end of shaft A¹³. Fig. 3 is a partial section in about the line x, Fig. 2, the rack for actuating the nail assorting mechanism, together with the parts at the lower end of the shaft supporting the nail box carrier being omitted. Fig. 3^a is a detail showing the guide-plate detached. Fig. 4 is a partial section below the line x', Fig. 2. Figs. 4^a and 4^b are details of the parts connected with the lower end of the shaft A¹³. Fig. 5 is a detail showing the heel blank feeder in plan; Fig. 6, a longitudinal section thereof, and Figs. 7 and 8 are sections respectively in the lines x³—x⁴, Fig. 5. 85

Referring to the drawings, A represents portions of the frame-work, the same being of any usual or suitable shape to sustain the working parts, to be described. The main shaft A'; its pinion A² engaging a gear A³; 90 the shaft A⁴ on which the gear A³ is loosely mounted, said shaft having two cams B, N, and a crank pin 42; the shaft n⁶ rotated in some suitable manner and provided with an eccentric to reciprocate a link n⁷; a nail assorting mechanism having as part of it a table C; the main nail-road-ways g⁷, the auxiliary road-ways g⁸ below them supported on a foot g², detachably connected to a stand g', in turn fixed to the vertical bearing A^x of 100 the frame-work; the sector e¹² having its inner toothed end in engagement with the

toothed shank 51 attached to part of the nail assorting mechanism; the jaws b^7 pivoted at b^8 and carrying at their front ends the side compressors b^9 , represented chiefly by dotted lines in Fig. 4, said compressors being shown as attached to the levers by pins at x^4 ; the lever r , pivoted at r' and actuated by the cam B, said lever being joined at its lower end, by suitable toggle jointed arms, with the rear end of the levers b^7 ; the lever G' , pivoted at G^2 ; the rod G^5 pivoted to the right hand end of the lever G' and extended through a spring G^3 to normally keep the front end of the lever G' pressed toward the top of the side compressing dies with a yielding pressure determined by the screw G^7 ; the elbow lever A^7 to control the time of engagement of a suitable clutch with the constantly rotating gear A^3 ; the link A^8 connected to said lever A^7 and to a hand lever A^9 , pivoted at A^{10} and extended forwardly and provided with a hand piece and with a point A^{12} to engage at proper time and restrain the rotation of a plate A^{15} fast on the shaft A^{13} ; the lever E^3 co-operating with said clutch plate; the slide n' actuated by the cam N and connected by a link c^4 to a toggle lever c^6 , c^7 , shown by dotted lines in Fig. 1; the elbow link c^8 jointed to the toggle d , d' , the member d of the toggle being pivoted at d^2 , while the member d' of the toggle is pivoted to the shank of the plunger or die-carrier C^3 . the pulley E^7 ; the lever t^2 , t^3 ; the spring t^5 ; The belt E^6 to rotate the pulley E^7 continuously; the link 41 surrounding the crank-pin 42; and the breast-plate 32, see Fig. 3, are and may be all substantially as represented in said application, wherein the same letters are used to designate like parts, so that said parts need not be herein further specifically described. There is a slight difference, however, in the shape of the lever E^3 , a portion of the upper end of the lever being omitted from this present case, and herein the plunger C^3 , instead of carrying a plurality of heel-seat-dies, has fixed upon its upper portion a heel-seat-die E having suitable holes for the reception of suitable impaling pins 15 attached to a block 17 having a vertical movement by or through a suitable lever 9 pivoted on the block c^8 and forked to embrace a pin of the block 17. The outer end of the lever 9 enters a slot 12 in a bar 13 suitably attached to the frame-work, so that as the block C^3 is lifted by straightening the toggle d , d' , as provided for in said application, the lever 9 meets a portion of the bar 13 and is moved to force the impaling pins 15 into the heel then lying upon the heel seat die, the said pins aiding in withdrawing the compressed heel from the mold at a suitable time. The shaft A^{13} , common to the said application, is provided at its upper end with a carrier 300 suitably chambered to receive nail boxes f provided with suitable nail holes 91, and with a positioning hole e^8 for the reception of a positioning device e^7 carried by a driver-bar 301. The said nail boxes are normally acted upon by springs f^4 , which in their

normal position keep the nail holes in the nail boxes out of line or register with the holes 36 in what I denominate the "templet plate" f' 70 forming part of the carrier 300 and upon which rests the lower sides of the nail boxes. These nail boxes, the templet, the rotating carrier, the means for rotating the shaft A^{13} , and the positioning device e^7 are and may be substantially as in said application. The positioning device e^7 by its pointed end entering the hole e^8 in the nail box, moves the nail box against a spring f^4 to bring the holes 91 therein in line with the holes 36 in the templet, so that the drivers 302, connected with the driver-bar 301, in turn connected with the link 41 by the pin 40, may act upon the nails which are loaded automatically into the nail box through the nail assorting mechanism, 85 and main and auxiliary road-ways, as provided for in said application, and drive the said nails directly from the nail box into the heel then held in the compressing die, the upper or tread end of the heel being pressed 90 firmly against the templet, the top side of the nail box being acted upon at such time by the guide plate 304, it having a series of holes, see Fig. 3^a, to receive and guide the drivers, and at the same time the said plate 95 acts as an abutment to rest upon and hold the nail box and templet down firmly while the heel is being compressed vertically, the templet at such time constituting, it will be obvious, the upper side of the compressing 100 mold, the side or edge compressing die being closed upon and acting to compress the heel from edge to edge, and from its rear side toward its breast in time and order substantially as provided for in the said application. 105 The guide plate 304 has three side walls and an open side, as best represented in Fig. 3^a, two of its sides at its interior being provided with like notches 306, adapted to receive suitable projections 307, see Fig. 2, extended laterally therein from the driver-bar near the lower end.

In the application referred to, and as herein provided for, the spring G^3 normally acts to keep the front end of the lever G' pressed down in a yielding manner by a measured force, and herein the front end of said lever bears normally upon the side walls of the plate 304, but owing to the fact that the carrier 300 in its intermittent movements is 110 brought into the space below the plate 304, it becomes necessary, in order to avoid friction, to lift the plate 304 when the said carrier is to be moved, and this is provided for by the projections 307 on the driver-bar entering the notches 306, the said projections during the last part of the upward movement of the driver-bar meeting the upper ends of the notches referred to in the walls of the plate 304, thus lifting said plate or abutment 115 bodily from contact with the nail-boxes.

Herein I have provided means to positively lift the front end of the lever G' while the driver-bar is lifting the guide-plate 304. To

do this I have provided the wheel A³ with a cam projection 207, see Fig. 1, which acts on a cam roll 208, mounted in suitable ears on the rear end of the lever G'.

5 The driver-bar, as herein shown, has connected to it at its front side a rack 209 which engages the sector e¹² to effect the operation of the nail assorting mechanism.

I have herein provided means for automatically feeding a heel blank into position over the heel seat die when the plunger carrying the said die is depressed, or when the toggle d, d', is not straight.

The constantly rotating pulley E⁷ referred to, forms part of a clutch device, and, as also provided for in said application, it acts as a double clutch, that is, it actuates the clutch part w' to control the times of rotation of the shaft A¹³, and at its lower side it actuates a clutch part t loose with relation to the shaft A¹³ and having attached to it a cam 312, the said cam being kept on said shaft by a suitable pin or projection entering an annular groove 317, see Fig. 2^a, in the shaft A¹³ at its lower end. This cam 312 receives in its groove a suitable roll or stud of a lever 313, pivoted at 314, said lever having at its upper end a link 315, jointed at 316 to a carriage 317^x having a pusher 318 made adjustable on 25 said carriage by a suitable adjusting device 319, which may be a screw, so that the pusher may be adapted to heels of different sizes. A spring 320 is attached to one end of the carriage 317^x having a port 321, the heel blank being laid upon the said support and against the said pusher, said support sliding upon a slotted plate or guide-way 322 attached to a suitable stand 323 fixed to the frame-work. The carriage 317^x is 30 moved by the cam 312 in a direction to push a heel into position above and upon the heel seat die, when the latter is in its lowest position, and in the operation of the carriage in feeding a heel blank into working position. 35 The heel support 321 and carriage 317^x move substantially in unison until the end of said support meets a suitable stop, which may be a portion of the heel seat die, and thereafter the support remains at rest while the carriage 40 and pusher continue their movement to push the heel blank from the support into position upon the heel seat die to be elevated thereby at the next rise of the plunger C³, the said die putting the blank into the space between the 45 open side compressing dies carried by the jaws b⁷.

Referring to Figs. 6 to 8 it will be seen that the heel blank support is composed of separate side pieces made adjustable toward and 50 from each other by suitable adjusting devices 325, herein shown as right and left threaded screws.

This invention is not limited to the exact shape of the pusher or to the exact manner 55 shown of connecting it with the carriage, and it is obvious that the said pusher may form an integral part of the carriage and that as

an equivalent of adjusting the pusher or the carriage, the link 315 may have a right and left adjusting nut 336 as shown in Fig. 2. 70

In the production of boots and shoes, the heels thereof are generally applied automatically in a heel nailing machine, the heel blank being previously prepared for the nailing machine in various different ways. 75

The heel blanks are composed of "lifts" brought together in a suitable mold, and thereafter the blanks are pricked for the reception of nails, and the nails are loaded or inserted in the pricked holes by suitable drivers. 80

In all machines for compressing and loading heel blanks for heel nailing machines, the blank has always been pricked by awls to thus prepare it for the reception of the nails to be loaded therein. 85

In the machine herein described it will be noticed that the pricking of the blank is dispensed with and that the nails are driven directly from the nail box into the compressed heel, the machine containing suitable compressing jaws to co-operate with the heel seat die and hold the blank on all sides during the loading or driving operation. 90

Having described my invention, what I claim as new, and desire to secure by Letters 95 Patent, is—

1. In a machine for treating heel blanks, the following instrumentalities, viz:—a vertically movable plunger having a heel seat die adapted to mold the heel seat end of the heel blank; a vertically movable driver bar having a series of drivers and a driver guide plate, both arranged directly above the said heel seat die; and a rotatable carrier having a series of nail boxes or holders adapted to 100 be brought in succession into the space between the said heel seat die and driver guide plate whereby a heel blank after having been compressed vertically and while the carrier yet remains in the position in which the heel blank was compressed vertically, may have 105 nails driven directly into it from the nail box or holder then in position, substantially as described. 110

2. In a machine for treating heel blanks, 115 the following instrumentalities, viz:—a vertically movable plunger having a heel seat die to mold the heel seat end of a heel blank; a vertically movable driver bar having a series of drivers, and a yielding abutment, the 120 said drivers being arranged directly above the said heel seat die; and a rotatable carrier having a series of nail boxes or holders which are adapted to be brought one after another into the space between said heel seat die and abutment, whereby a heel blank may be compressed vertically, and while yet in the same position have a series of nails driven into it from the nail box or holder, substantially as 125 described.

3. In a machine for treating heel blanks, 130 the following instrumentalities, viz:—jaws to compress a heel blank from edge to edge, a vertically movable plunger having a heel

seat die shaped substantially as described to mold the heel seat end of the blank and located directly in line with the space between said edge compressing jaws; a vertically 5 movable driver bar having an attached series of drivers, and an abutment, the said parts being located at the opposite side of the space between said edge compressing jaws, and a rotatable carrier having a series of nail boxes 10 or holders, and means to move the same, whereby the said nail boxes or holders may be put successively in position between the said abutment and drivers on the one side and the said edge compressing jaws, and 15 means to actuate the plunger carrying the heel seat die to project a heel into the space between the said jaws and compress the same while the nail box or holder is in position under the abutment and nail drivers, to operate, 20 substantially as described.

4. In a machine for treating heels, the following instrumentalities, viz:—a reciprocating driver-bar; a series of drivers, a heel seat die, and a vertically movable plunger on which 25 it is mounted, combined with an intermittently rotatable carrier having a series of nail boxes, which are put in succession in the space between said drivers and heel seat die, edge compressing jaws, and a yielding guide 30 plate to co-operate with the heel seat die during the vertical compression of the heel blank, substantially as described.

5. In a machine for treating heels, the following instrumentalities, viz:—a reciprocating 35 plunger having a heel seat die; a rotatable carrier shaped to support a series of nail boxes and provided with holes to act as a templet and bear against the tread end of the heel, and a series of nail boxes mounted 40 thereon, combined with a guide-plate to act upon and co-operate with the nail box to keep it and the templet down during the vertical compression of the heel blank, substantially as described.

45 6. In a machine for treating heels, a carrier, a nail box mounted thereon, combined with a driver-bar; a series of drivers, and an independent driver guide-plate adapted to co-operate with the nail box and keep the same 50 in place during the nail driving and heel compressing operations, substantially as described.

7. In a machine for treating heels, a carrier, a nail box thereon, and a guide plate arranged at one side the nail box, combined with devices to move the guide plate away from the nail box when the carrier with its nail box is to be moved, and with a heel seat die, a plunger to move it, edge compressing 60 dies, and a yielding abutment, substantially as described.

8. A nail driver bar having projections, combined with a driver guide plate having notches to be engaged by said projections, to 65 operate substantially as described.

9. In a machine for treating heels, a driver bar and a series of drivers, a carrier, a series

of nail boxes thereon, a portion of the carrier serving as a templet, combined with a plunger, a heel seat molding die carried thereby, 70 shaped substantially as represented to mold the heel seat end of the heel blank, impaling pins, and devices to actuate the same, substantially as described.

10. In a machine for treating heels, a driver 75 guide plate, combined with a yielding abutment, and means for automatically releasing the abutment to permit the guide plate to be moved, substantially as described.

11. In a machine for treating heels, a driver 80 guide plate, combined with a yielding abutment, and means for automatically releasing the abutment to permit the guide plate to be moved, and a movable carrier having a series 85 of nail boxes, substantially as described.

12. In a heel blank treating machine, a cam, a clutch to operate the cam intermittently, compressing dies for a heel blank, combined with a heel blank support, a guide-way in 90 which it is adapted to slide, a pusher, a carriage upon which it is mounted, and actuating devices between said cam and carriage, to operate, substantially as described.

13. In a heel treating machine, a heel blank feeder consisting of an adjustable heel support to thereby adapt it to heels of different sizes, combined with a carriage, and a pusher 95 adjustably mounted thereon, to operate, substantially as described.

14. In a machine for treating heels, a heel 100 blank feeder comprehending a sliding carriage, a heel support, and a yielding connection between said carriage and support, to operate, substantially as described.

15. In a machine for treating heels, a feeder 105 comprehending a support for the heel, a carriage having a pusher, and adjusting devices to enable the normal position of the pusher with relation to the support to be changed according to the size of the heel, substantially 110 as described.

16. In a machine for treating heel blanks, compressing jaws to compress the blank from edge to edge, an independent breast gage against which the edge compressing jaws force 115 the breast of the blank during the edge compressing operation, combined with a heel seat die, a templet, and a reciprocating driver-bar having a gang of drivers to drive nails directly from the templet into the blank while 120 yet held between the compressing jaws and breast gage, substantially as described.

17. In a machine for treating heels, the following instrumentalities, viz:—edge compressing jaws; a breast support; a heel seat 125 molding die to enter the space between the said jaws, a templet to close the opening between said jaws opposite the heel seat die, a nail box supported by said templet, and an independent guide-plate as 304, adapted to 130 bear upon said nail box and hold it in place during the driving operation, combined with a gang of drivers and actuating means therefor, substantially as described.

18. In a machine for treating heel blanks, an edge compressing mold, a vertically movable plunger having a heel seat die and adapted to place a heel in position in the said 5 mold, combined with a movable series of nail boxes or holders adapted to be brought in succession at one side of said mold and opposite the heel seat die, a vertically movable driver bar having a series of drivers, and an 10 abutment located immediately above the path of movement of the said heel seat die and co-acting with the nail box or holder to resist
- the upward pressure of the heel seat die and to aid in retaining the said nail box or holder in place during the driving operation, substantially as described.
- In testimony whereof I have signed my name to this specification in the presence of two subscribing witnesses.

CHARLES W. GLIDDEN.
